UNITED STATES PATENT OFFICE.

JAMES GIRTEN, OF CHICAGO, ILLINOIS.

ELEVATOR DOOR LOCK.

Application filed December 19, 1921. Serial No. 523,266.

To all whom it may concern:

Be it known that I, JAMES GIRTEN, a citizen of the United States, and a resident of the city of Chicago, county of Cook, and State of Illinois, have invented certain new and useful Improvements in Elevator Door Locks, of which the following is a specification:

My invention relates to elevator door locks, and has for its object the provision of safety devices in connection with latching means by reason of which the elevator driving means may be thrown out of operation, and which is particularly adapted for application to double doors of the type ordinarily employed for elevators.

Other objects will appear hereinafter.

The invention consists in the combination and arrangements of parts hereinafter described and claimed.

The invention will be best understood by reference to the accompanying drawings forming a part of this specification, and in which,

Fig. 1 is a side elevation of the invention, showing the parts in operative position in full lines, and in inoperative position in dotted lines, the cover of the latch casing having been broken away to expose the operative parts of the mechanism contained therein;

Fig. 2 is a side elevation of the invention;

Fig. 3 is a sectional view on line 3—3 of Fig. 1;

Fig. 4 is a front elevation of the latch actuating mechanism; and

Fig. 5 is a sectional view on line 5—5 of Fig. 4.

The invention consists of improvements in latching, and making and breaking devices, of the type disclosed in my companion application, Serial No. 419,466, filed October 25, 1920, which has matured into Patent No. 1425762, August 15, 1922.

Referring to the drawings 1 and 2 designate oppositely disposed sliding elevator doors. Disposed above the doors in proper position is a casing 3, which contains the latching, and making and breaking mechanism.

Pivotedly mounted in the casing 3 by means of a suitable pin 4 is a latching member 5, preferably in the form of a bell crank lever, the leg 6 of the lever having a catch 7 at its outer end and a leg 8 being provided with a segmental extension 9, as shown in Fig. 1 of the drawings. A lug

10 is mounted on the inner side of the leg 6 for a purpose to be explained. The member 5 is so arranged that it normally tends to fall into operative position by its own weight, such falling movement being limited by a stop 11 in the casing 3, the rearward movement of the member 5 being limited by a stop 12 mounted at one side of the casing 3. Pivotedly mounted adjacent the member 5 is a swinging arm 13, such arm preferably extending below the leg 6 and being held off center by reason of its engagement with the lug 10. The inner surface of the arm 13 is preferably provided with notches 14 adapted to engage the lug 10, the arrangement being such that upward movement of the leg 6 permits the arm 13 to swing toward center, thereby causing the engagement of one or the other of the notches 14 with the lug 10, which retains the member 5 in raised position until such time as the arm 13 is again moved off center which permits the member 5 to drop of its own weight.

Mounted on the extension 9 of the member 5 by any suitable means are contact plates 15 and 16, such plates being suitably insulated from the extension 9 and from each other. Disposed above said extension is a suitable bracket 17, which preferably carries spring members 18 and 19 which have their inner ends interposed in the power wires 20. Mounted on the outer ends of the members 18 and 19 are shoes 21 and 22, such shoes being adapted to ride on the contacts 15 and 16. The arrangement is such that when the member 5 is in operative position, both of the shoes 21 and 22 engage the contact 16, affording an uninterrupted circuit through the power wires 20, but when the member 5 is moved to inoperative position, the shoe 21 engages the contact 15 and the shoe 22 the contact 16, thereby interrupting the circuit through the power wires 20.

Mounted on the door 1 is a plate 23, carrying on its upper end a hook member 24, which is adapted to be engaged by the catch 7 when said catch is in operative position. Pivotedly mounted on the plate 23 is a bar 25, such bar having its inner end positioned beneath the catch 7 and being adapted to raise said catch by upward movement thereof. Pivoted to the opposite end of the bar 25 is a rod 26, the lower end of such rod being slidably mounted in a supporting plate 27, and being limited in its upward

movement with respect thereto, by a collar 28 mounted on its end and engaging a stop 29, and limited in its downward movement by engagement with a socket 30 in the bracket 31. The rod 26 is normally urged to its uppermost position by means of a spring 32 secured thereto and to an extension 33 mounted on the plate 23. The rod 26 is also provided with a shoulder 34 for a purpose as will presently appear.

Pivottally mounted on the plate 23 is a latch 35, the head 36 of such latch being adapted to engage a hook member 37 mounted on the door 2, the head 36 of the latch 35 being weighted to normally engage the hook 37. The tail 38 of the latch 35 projects beneath the shoulder 34 on the rod 26.

In operation, on a downward movement of the rod 26, through the bar 25, the member 5 is raised, disengaging the catch 7 from the hook 24, and also disengaging the latch 35 from the hook 37, through the medium of the shoulder 34 engaging the tail 38 of such latch. Closing of the doors releases the member 5 by means of engagement of the hook 24 with the pivoted arm 13, permitting the member 5 to drop to operative position and the latch 35 at the same time rides up and of its own weight drops over the hook 37. In order to permit convenient inspection of the mechanism in the casting 3, without removing the covering therefrom, I insert in such covering a plate 39 of glass, isinglass, or other suitable transparent or translucent material.

While I have illustrated and described the preferred form of construction for carrying my invention into effect, this is capable of variation and modification without departing from the spirit of the invention. I, therefore, do not wish to be limited to the precise details of the construction set forth, but desire to avail myself of such variations and modifications as come within the scope of the appended claims.

Having described my invention, what I claim as new and desire to secure by Letters Patent, is:

1. A device of the character described comprising a movable latching member provided with a plurality of contact means thereon insulated one from the other; and a plurality of contact members arranged in a circuit and in position to engage said contact means, movement of said latching member to one position causing said contact members to engage one of said contacts, and movement to another position causing said member to engage separate contacts; substantially as described.

2. A device of the character described comprising a latching member, means with which said latching member normally engages for holding a door against movement; means for unseating said latching member;

means for retaining said latching member in unseated position; means whereby said latching member is released from said retaining means by engagement of said holding means; a plurality of contact means mounted on said latching member and insulated one from the other; and a plurality of contact members arranged in a circuit and in position to engage said contact means, movement of said latching member to operative position causing said members to engage one of said contacts, and movement to inoperative position causing said members to engage separate contacts; substantially as described.

3. A device of the character described, comprising a latching member in the form of a bell crank lever, one arm of which is provided with a curved extension, and the other arm of which forms a catch; a plurality of contact means mounted in the curved extension of said latching member and insulated one from the other; and a plurality of contact members arranged in a circuit in position to engage said contact means, movement of said latching member to one position causing said contact members to engage one of said contacts and movement to another position causing said member to engage separate contacts; substantially as described.

4. A device of the character described comprising a latching member in the form of a bell crank lever, having a curved extension on one leg thereof, and a catch on the other leg thereof; means with which said latching member normally engages for holding a door against movement; means for unseating said latching member; means for retaining said latching member in unseated position; means whereby said latching member is released from said retaining means by engagement of said holding means; a plurality of contact means mounted in the curved extension of said latching member and insulated one from the other; and a plurality of contact members arranged in a circuit in position to engage said contact means, movement of said latching member to operative position causing said contact members to engage one of said contact means, and movement to inoperative position causing said contact members to engage separate contacts; substantially as described.

5. A device of the character described comprising a latching member, means with which said latching member normally engages for holding a door against movement; means for unseating said latching member; means for retaining said latching member in unseated position; means whereby said latching member is released from said retaining means by engagement of said holding means; an extension on said latching

member having a plurality of contact means arranged therein and insulated one from the other; and a plurality of contact fingers arranged in the elevator operating circuit, 5 and riding on said contact means, so that when the latching member is in operative position both of said fingers engage one of said contact means, and when the latching member is in inoperative position one of 10 said fingers engages one of said contact means and another of said fingers engages another of said contact means, substantially as described.

6. In a device of the character described 15 comprising a movable latching member; means with which said latching member normally engages for holding a door against movement; a second door co-operating with said first mentioned door; means for disengaging said latching member from said first mentioned door; means for retaining said latching member in unseated position; means whereby said latching member is released from said retaining means by engagement of said holding means; and an auxiliary latch actuated simultaneously with said latching member for holding said doors together; substantially as described.

7. In a device of the character described 30 comprising a movable latching member; means with which said latching member normally engages for holding a door against movement; a second door cooperating with said first mentioned door; means for disengaging said latching member from said first mentioned door; means for retaining said latching member in unseated position; means whereby said latching member is released from said retaining means by engagement of said holding means; an electric 35 switch associated with said latching member for making and breaking a circuit, and an auxiliary latch actuated simultaneously with said latching member for holding said doors together, substantially as described.

8. In a device of the character described 40 comprising a latching member adapted to engage a door to permit movement thereof; a latching arm held in inoperative position by 45 said latching member and being permitted to assume engaging position by the movement of the latching member to inoperative position; means for disengaging said latch-

ing arm; a second door co-operating with said first mentioned door; and an auxiliary 55 latch actuated by said disengaging means to hold said doors together, substantially as described.

9. In a device of the character described 60 comprising a latching member adapted to fall to operative position of its own weight; means with which said latching member engages for holding a door against movement; a latching arm held in inoperative position by said latching member and being permitted to assume engaging position by movement of the latching member to inoperative position; means for unseating said latching member to permit said latching arm to move to operative position; means whereby said 65 door holding means engages said latching arm to permit said latching member to return to operative engagement; a second door co-operating with said first mentioned door; and an auxiliary latch operable by said 70 latching member; unseating means to hold said doors together, substantially as described.

10. In a device of the character described 75 comprising latching means; a door engaged by said latching means to prevent movement thereof; a second door co-operating with said first mentioned door; means for operating said latching means; and an auxiliary latch operable by said latching means for holding said doors together, substantially as described.

11. In a device of the character described 80 comprising a latching means; a door held against movement by said latching means; a second door co-operating with said first mentioned door; means for actuating said latching means; and an auxiliary latch normally engageable by gravity to hold said doors together, and adapted to be unseated simultaneously with said latching means by said actuating means, substantially as described.

In testimony whereof I have signed my name to this specification in the presence of 100 two subscribing witnesses.

JAMES GIRTEN.
